PROCESS FOR DEHYDRATING ALIPHATIC ACIDS BY A COMBINED EXTRACTION-DISTILLATION METHOD

Donald F. Othmer, Brooklyn, N. Y., assignor, by mesne assignments, to Tennessee Eastman Corporation, Kingsport, Tenn., a corporation of Virginia

Application April 7, 1938, Serial No. 200,746

5 Claims. (Cl. 202—42)

This invention relates to a process and solvents for the dehydration of aqueous solutions of lower aliphatic acids, and more particularly to a process for the production of substantially concentrated or glacial acetic acid from aqueous acid solutions, wherein heating requirements are minimized.

This application is in part a continuation of my copending application Serial No. 88,823, filed July 3, 1936, now Patent No. 2,170,834.

Aliphatic acids such as acetic acid are employed in large quantities industrially. These acids are in many instances obtained as by-products or in their manufacture are produced in the form of dilute aqueous solutions. Before the acids are suitable for certain uses they must be dehydrated or concentrated. As pointed out in my copending application, various distillation processes for dehydrating aliphatic acids have been suggested. Since many of the processes involve rather extensive distillation treatments, one of the largest factors of cost is the heat input required.

Certain investigators have developed processes designed to reduce the heat consumption. For example, it has been proposed to distill aqueous solutions azeotropically and pass the azeotrope vapors in heat exchange with an independently prepared extract, thereby producing two independently concentrated acid residues.

It has also been proposed to partially azeotropically dehydrate the acid and then extract the partially dehydrated acid, subjecting the resultant extract to heating by means of the aforementioned azeotrope. Other processes have been suggested in the prior art employing benzene and the like as entrainers.

It has been suggested that various ketones alone might be used as withdrawing agents. Also, various mixtures of ketone with benzene, esters or ethers for use as entraining agents has been suggested. I have discovered a novel agent and method of operation distinguishing from the prior art which are more efficient in certain respects than prior art entrainers and processes and possess other advantages.

This invention has for one object to provide a process for the dehydration of aqueous solutions containing at least one aliphatic acid. Another object is to provide a combination process for the dehydration of aqueous solutions containing at least one aliphatic acid, which process is more economical of heat and otherwise more advantageous than certain prior art processes. A still further object is to provide a combination proc-

ess for concentrating aqueous aliphatic acid solutions wherein relatively pure concentrated acid may be recovered. A still further object is to provide a process for the concentration of lower aliphatic acids which may be applied to acids from various sources such as aqueous acid solutions from synthetic acid production, aqueous acid solutions from fermentation processes, pyrolygneous liquor and various other sources of aqueous acid. A still further object is to provide a combination process for dehydrating aqueous aliphatic acid solutions which process includes straight distillation in combination with an azeotropic distillation employing vaporous heat from the straight distillation. Still another object is to provide a process for concentrating lower aliphatic acids which is continuous.

A further object is to provide novel entraining agents which may be employed in processes for the dehydration of lower aliphatic acids. Another object is to provide a novel mixed ketone entraining agent. Still another object is to provide a combination entraining agent which may be used both as an extracting agent and as an entraining agent. Still another object is to provide an agent which is particularly adaptable for use in the treatment of aqueous solutions containing lower aliphatic acids in high concentration. Still another object is to provide a process for the dehydration of aqueous solutions containing lower aliphatic acids which process includes a particular type azeotropic distillation. Other objects will appear hereinafter.

I have found an improved process wherein very high heat economy may be obtained. I have found that it is advantageous that the water be removed from a dilute aliphatic acid solution by cold extraction and from a more concentrated solution by azeotropic distillation, provided the proper agents and process steps are employed.

For a more complete understanding of my invention, reference is made to the attached drawing, which diagrammatically represents an apparatus set-up which might be employed for carrying out my invention.

In the attached drawing, 1 represents a feed tank or other container for holding the aqueous aliphatic acid solution to be treated. This tank is connected to an extraction device 3, by means 50 of conduit 2.

It is, of course, desirable that an efficient unit or units be employed. For example, this device might comprise an open column (with two liquid phases and droplets of the heavier liquid falling 55 through the upper or lighter liquid phase, and

droplets of the lighter liquid rising through the lower or heavier liquid phase). Such a device is relatively simple and economical to construct and operate. Two or three 60-80 ft. extractors would be employed.

The feed tank 1 is also connected by means of another conduit 4 to a pre-evaporator or evaporation still 6. This device 6 is connected by means of conduit 7 to the immediate section of an azeotropic distillation column 8. Inasmuch as this column may be substantially the same as that disclosed in Fig. 3 of my copending application 88,823 or as shown in my prior Patents 2,028,800 and 2,028,801, further description thereof is unnecessary. The vapor off-take conduit 9 passes through the condenser-evaporator 11.

This device might comprise a plurality of horizontal tubes through which vapors may flow, and housed by an external chamber adapted for containing liquid. A preferred type of device would be the outside vertical calandria type having either natural or forced circulation. Because of the high rate of heat transfer secured by this type of evaporator substantially full advantage of the low temperature drop between the vapors giving up the heat and the liquid being heated, could be obtained. It is also possible to employ several evaporating chambers in series or other arrangements.

The evaporator 11 is connected by conduit 12 to a decanter 13 which in turn is connected through conduit 14 to column 8. The decanter is also connected by conduit 16 to an auxiliary column 17 which is in turn connected through conduit 18 to the condenser evaporator 11.

The condenser evaporator feeds through the plurality of conduits 21, 22 to intermediate sections of another column 23. This column is similar to column 8; hence, requires no further description excepting to point out that both columns 8 and 23 have heating means as at 24 and 26.

The condenser evaporator 11 is connected by conduit 27 to the extraction device 3 already described.

Column 23 is also provided with several conduits 28, 29, 31, 32, 33 and the condenser 34 and decanter 36, which serve to permit carrying out of distillation operations as well as to inter-connect the device with extractor 3. The aqueous outlet 37 leads to a solvent stripping column 38 of conventional construction.

One feature of particular importance which the apparatus set-up embraces is that extract column 23 is directly connected by means of conduit 41 to an intermediate section 42 of the azeotropic column 8.

As indicated, the apparatus has been shown more or less diagrammatically and in flow sheet arrangement, and certain modifications may be introduced therein. For example, if desired, partial heating of the low boiling solvent stripping column 38 could be carried out by means of heating from the azeotropic system in the same way that the extract column is heated.

In carrying out my process, a part of the aqueous aliphatic acid to be dehydrated is drawn off through conduit 2 and is extracted in 3 in the liquid phase by a low boiling point solvent. The aqueous layer, substantially free of aliphatic acid, is conducted through 37 to column 38 where it is stripped to recover dissolved solvent. The extract layer passing through the conduit 27 is evaporated in the condenser evaporator 11 above the azeotropic column. By employing suitable solvents, as will be described in further detail

hereinafter, it is possible to evaporate the solvent layer substantially completely. It is to be noted, however, in my process, that the unevaporated liquid goes through conduit 22 to the extract column 23.

The vapors from the device 11 pass to an intermediate section of column 23, where they are rectified and a distillate passes out through the vapor outlet conduit 28. This distillate is condensed at 34 and passes to the decanter 36. Because of the type of solvent employed, only a small amount of water is brought over and separated from solvent in the decanter. The water layer in the decanter may be passed through conduit 32 into the water column along with that from the extractor for stripping solvent therefrom. The solvent layer from the decanter 36 is divided, a minor part being returned through 31 for reflux, the balance being returned through conduit 33 to the cold extraction.

Referring again to extract column 23, as already indicated, another intermediate section thereof receives the feed through conduit 22 of excess unevaporated liquid from the condenser-evaporator 11. However, by virtue of the base heater 24, complete separation of all the low boiling point solvent is assured. Consequently, it will be noted that not only does column 23 discharge an aqueous acid but this aqueous acid is discharged through conduit 41 into an intermediate section 42 of the azeotropic column 8. It will be observed in my process that it is not necessary to remove water in the extract column 23, excepting that which is removed in separating the solvent from the vapors fed to the unit. This is of some importance, because solvents employed for extraction sometimes have poor entraining capacity for azeotropic distillation. Hence, in my process most water which is removed by distillation, is removed by means of a particular type highly efficient azeotropic agent by procedure hereinafter described.

That is, in my process the strengthened but still aqueous acid from the bottom of column 23 is run as a liquid fed through conduit 41 to the azeotropic column 8 using a high boiling point efficient entraining agent in the particular manner to be described. This acid is then substantially or completely dehydrated in column 8. The azeotropic vaporous mixture from column 8 is condensed in the condenser-evaporator and separated in the decanter 13. If desired, this decantation may be carried out at a temperature a few degrees below the boiling point of the azeotrope. The water layer from the decanter flows through conduit 16 to column 17 where any solvent is stripped out and returned through conduit 18 to join the main azeotropic vapors in condenser-evaporator 11.

It is apparent from the preceding that the balance between the extraction procedure and the azeotropic procedure depends upon the amount of heat passed in the condenser evaporator 11, which in turn depends on the amount of water removed in the azeotropic distillation 8 which in turn depends to some extent on the strength of liquid from the base of extract column 23, returned through conduit 41. Therefore, if a comparatively dilute liquid comes from the extract column, more heat will be required by the azeotropic column 8 and more heat will be given up in the evaporator condenser 11. In the preferred operation of my process the amount of heat available in the azeotropic mixture or vapors passing out through conduit 9, should be

not substantially greater than that required to evaporate the extract in the condenser evaporator 11. I will point out in detail hereinafter wherein I am able to control this factor to some extent. If the heat is greater an additional condenser may be inserted in lines 9 or 12, for example.

On the other hand, if a more concentrated liquid comes from the base of extract column 23, it is possible that the heat required to evaporate the extract in the condenser evaporator will be less than that supplied to the condenser evaporator by the vapors passing out through conduit 9. I have found that in this case I am able to control the relative heat ratios by feeding an additional amount of the original aqueous acid solution through conduit 4 to the pre-evaporator 6 from which the acid reaches column 8 through the conduit 7. The removal of the water in this additional aqueous feed requires an additional amount of heat in the azeotropic distillation which increases the amount of heat passing to the evaporator condenser to an amount sufficient to evaporate the extract, or that part of the extract which it is desired to evaporate. That is, I have found by controlling the flow of aqueous acid through 4 either directly to the column or indirectly through the pre-evaporator 6 that I am able to more or less control and balance the heat requirements in my process.

While as I have pointed out, the most effective balance between the extraction part of the process and the azeotropic distillation is obtained when the water to be removed in the azeotropic distillation requires that amount of heat in the azeotropic mixture which, when transferred in the condenser evaporator 11, will just evaporate the amount of extract desired evaporated, such conditions may be altered in commercial use. That is, this balance and interrelationship may be affected by various factors such as (1) strength of dilute acid to be handled, (2) partition coefficient of acetic between low boiling solvent and water, (3) water solubility in low boiling solvent at different amounts of acetic, (4) efficiency of extractor and extraction operation, (5) boiling point of low boiling solvent and its azeotropic mixture (if any) with water, (6) efficiency of condenser-evaporator in its evaporative function, (7) azeotropic mixture ratio of the high boiling solvent, (8) mutual miscibility of high boiling solvent with water, (9) partition coefficient of high boiling solvent with water for acetic acid and other factors which determine its azeotropic efficiency.

However, as pointed out, I am able to control my process to some extent by control of the quantity of aliphatic acid fed to the azeotropic column 8 by way of the pre-evaporator.

The feed from the extract column 23 through conduit 41 may, of course, be passed into the pre-evaporator 6 rather than to the intermediate section of the column as at 42. However, this is not necessary because the preceding treatment in the extract column, condenser-evaporator and extraction, has eliminated the bulk of the salts or other impurities which it might otherwise be necessary to remove in pre-evaporator 6.

As has been pointed out, the acid solvent used in the extractor 3 should have a boiling point at least, and preferably more, than 20-30° lower than the azeotropic boiling point with water of the agent employed in the azeotropic column 8. For example, agents such as ether, chloroform, ethyl acetate, etc., could be employed in the ex-

traction apparatus 3 and my novel mixed ketone entrainers to be described hereinafter employed in the azeotropic distillation column 8.

I have found that mixed ketone agents comprise entrainers which are particularly useful in processes for dehydrating aqueous solutions of aliphatic acids. For example, a mixture of 65 to 70% di-isopropyl ketone and 25 to 30% of ethyl isopropyl ketone is an excellent agent for use in accordance with the procedure set forth herein. This mixture of di-isopropyl and ethyl isopropyl ketone has a boiling range of 114 to 127° C. and weighs approximately 6.8 pounds per gallon at 68° C. It should be noted that this is a mixture of a symmetrical ketone and an unsymmetrical or mixed ketone. The above proportions are set forth for the purposes of illustration and may be varied.

I have carried or had carried out under my direction a number of tests employing the above-mentioned mixture of di-isopropyl and ethyl isopropyl ketone and have found this ketone mixture to have an excellent withdrawing power bringing over almost one part of water for four parts of ketone distilled. The azeotropic boiling point is approximately 89° C. at a normal barometer. These figures would vary somewhat in a commercial installation because there would be a slight tendency to lose the lower ketone by evaporation loss and thus to make the azeotropic boiling point higher and to bring over a greater amount of water in the azeotropic mixture.

This material is an excellent withdrawing liquid also because it has a very good extraction coefficient for acetic acid in contact with water, which is unique in that it improves with higher acid concentrations. It tolerates a large amount of acid, which means that it could be used as an extracting agent for relatively high acid concentrations. A table follows showing the relation of acid strength in each layer.

Acetic acid, grams per 100 cc.

	Water layer	Ketone layer
45	2.19	.71
	5.08	1.78
	9.85	3.73
	20.7	9.75
50	26.8	14.7
	34.0	20.2
	37.7	27.7

There is only a single layer above about 40 grams acetic per 100 cc. It, therefore, gives a very low acid content in the water discharged from the decanter because it has a tendency to extract the acid from the vapors rising in the column. It is considerably more insoluble in water (and water in it) than certain esters. It will be more stable in that there is, of course, no hydrolysis and the material originally charged is practically the same from month to month in operation.

Because of its lower mutual solubility with water, less water is returned to the azeotropic column and less ketone is discharged to the stripping column if an apparatus as shown in Othmer 2,028,800 is employed.

The entraining agent employed in column 8, whether it be my preferred mixed ketones or some other agent such as ethyl hexyl ether or other high boiling point ether is preferably employed in the following special manner. That is, the mixture of acid and water fed to column 8 through conduits 7 and 41 is azeotropically dis-

tilled with the agent so that the bulk, but not all of the water, is removed in the azeotropic section of the column. It will be further observed that in my process preferably all of the water (even that separated in the lower part of the column by straight distillation) works its way up through the azeotropic section and is thus finally discharged by azeotropic distillation. This azeotrope of entrainer and water is removed through conduit 9, decanted at 13, and the entrainer returned through 14 to the head of the column. Provided an entrainer such as my mixed ketones is employed, which has the property of extracting aliphatic acids even at high acid concentration, the acid losses through 9 will be reduced to a minimum. That is, the mixed ketone agent through 14 in flowing down column 8, will remove the acid from the vapors passing upwardly in the column.

The water remaining in the acid after the bulk of the water has been removed by azeotropic distillation, is more or less continuously eliminated from the acid by straight distillation in the bottom of column 8. The vaporous heat from this straight distillation is transmitted to the azeotropic distillation and consumed therein.

Or, if it is desired, my novel ketone mixture may be employed in other type extraction or distillation processes for dehydrating aliphatic acids. That is, I have found that my novel ketone mixtures have considerable value for use in azeotropic distillation alone for the production of dehydrated aliphatic acid. For example, a mixture of the ketones may be supplied to the decanter or other inlet to a continuous azeotropic distilling system. A portion of the ketone would be permitted to flow back through the upper part of the distillation column. Aliphatic acid (preferably vaporous) to be concentrated would be supplied to an intermediate section of the column at some point below the aforementioned ketone return. This is advantageous because as I have already pointed out, my ketone mixtures tend to extract the acid from the vapors arising in the column.

A vaporous mixture comprising the several ketones and water would be removed from the head of the column, condensed and passed to the decanter. In the decanter the several ketones form a distinct layer, thereby separating from water and this ketone layer may be returned to the column as already described. The water layer may be withdrawn to an auxiliary column where any ketones entrapped or otherwise lost therein may be removed prior to discharging the water to waste. These removed ketones are preferably conducted through the condenser and back to the decanter from which they are returned to the column. By this procedure the column is prevented from becoming unbalanced and operation is otherwise improved.

Preferably the amount of ketones employed is such that the lower portion of the column comprises only aliphatic acid and water. This may be accomplished by employing insufficient ketone mixture in the system to furnish a content in the lower portion of the column. The water remaining in the acid may be distilled therefrom in a manner such as described with respect to column 8.

The dehydrated acid would preferably be withdrawn from the base of the column in a vaporous condition. If the procedure described is employed, a relatively pure acid uncontaminated by the ketone mixture will be recovered.

From the preceding it is apparent that I have provided a novel process wherein heating requirements may be reduced to a minimum. This is possible because in my process substantially all of the water removed by distillation is removed using a highly efficient entraining agent. The heat of this mixture is substantially recovered. If desired, the decantation in 13 may take place at a temperature of a few degrees below the condensation point of the azeotrope. Also, in my process, the heat of the hot aqueous acid base of column 23 is not lost because said acid is fed to distillation column 8. In addition, there are various other features disclosed herein, all contributing to rendering my process particularly efficient. While I have described certain procedure for my preferred embodiment, inasmuch as I have found such procedure to produce most optimum results, it is to be understood that my invention embraces wider aspects. For example, as described, my novel ketone mixtures may be employed in various ways in the dehydration of aliphatic acids. Although I have shown an extraction column and various other apparatus units, it is to be understood that other devices may be employed. Hence, I do not wish to be restricted in my invention excepting insofar as may be necessitated by the prior art and by the spirit of the appended claims.

What I claim and desire to be secured by Letters Patent of the United States is:

1. A process for dehydrating aqueous acetic acid solutions, which comprises forwarding such solutions in the vaporous state into an intermediate section of a distillation column containing a mixture of a symmetrical ketone with an unsymmetrical ketone, vaporizing symmetrical ketone, unsymmetrical ketone and water from the column, separating the symmetrical and unsymmetrical ketone mixture from the water and returning this ketone mixture to the distillation column at a point substantially above the vaporous feed, whereby said ketone mixture flows countercurrent to the vapors in the column undergoing distillation, and withdrawing the dehydrated acid from below the vaporous feed.
2. A process for dehydrating aqueous solutions containing at least one lower aliphatic acid therein, which comprises conducting such solutions in the vaporous state into an intermediate portion of a distillation column, said column containing a mixture of 50% to 80% di-isopropyl ketone with 15% to 40% ethyl isopropyl ketone as a water-withdrawing agent, vaporizing di-isopropyl ketones, ethyl isopropyl ketone and water from the column, separating at least a part of the di-isopropyl ketone and ethyl isopropyl ketone from the water and returning the separated ketones to the distillation at a point substantially above the vaporous feed, whereby the returned ketones flow countercurrent to the materials in the column undergoing distillation, and withdrawing dehydrated acid from a point below said vaporous feed.
3. A process for dehydrating aqueous solutions containing at least one lower aliphatic acid, which comprises passing such solutions in a vaporous condition into a distillation column containing a mixture of a symmetrical ketone with an unsymmetrical ketone, vaporizing symmetrical ketone, unsymmetrical ketone and water from the column, separating the symmetrical and unsymmetrical ketone mixture from the water and returning this ketone mixture to the distillation column at a point substantially above

the vaporous feed, whereby said ketone mixture flows countercurrent to the vapors in the column undergoing distillation, and withdrawing the dehydrated acid from below the vaporous feed.

4. A process for dehydrating aqueous solutions containing at least one lower aliphatic acid therein, which comprises conducting such solutions in the vaporous state into an intermediate portion of a distillation column, said column containing a mixture principally of methyl propyl ketone with di-ethyl ketone as a water-withdrawing agent, vaporizing methylpropyl ketone, di-ethyl ketone and water from the column, separating at least a part of the ketone mixture of said methylpropyl ketone and said di-ethyl ketone from the water and returning the separated ketone mixture to the distillation at a point substantially above the vaporous feed, whereby the returned ketones flow countercurrent to the materials in the column undergoing distillation, and 20 withdrawing dehydrated acid from a point below said vaporous feed.

5. A process for dehydrating aqueous aliphatic acid solutions which comprises conducting such solutions in a vaporous state to an intermediate section of the distillation system, the system containing a mixture of a symmetrical ketone with an unsymmetrical ketone, distilling off symmetrical ketone, unsymmetrical ketone and water from the distillation system, passing at least a part of the vapors so distilled off in heat exchange with a cold mixture of acid, solvent, and water for cooling said vapors, separating symmetrical and unsymmetrical ketone vapors from water and returning this separated ketone mixture to the distillation at a point substantially above said vaporous feed, whereby said ketone mixture flows countercurrent to the components in the column undergoing distillation and withdrawing dehydrated acid from below said vaporous state.

DONALD F. OTHMER.
